UNITED STATES PATENT OFFICE.

HULBERT SANNER, OF CHICAGO, ILLINOIS, ASSIGNOR TO LOTHAR EDERER, OF CHICAGO, ILLINOIS.

TIME SWITCH.

Application filed January 2, 1925. Serial No. 263.

My invention relates to improvements in time switches particularly adapted for use in connection with program machines and has for one object to provide a distributing element for a switch which can be easily and conveniently removed from the switching zone for correction or change. Another object is to provide a removably mounted cylinder or drum and to equip it with means whereby the operator will always be compelled to return it to proper position with respect to the balance of the mechanism so as to insure against distortion of the parts or inaccurate positioning. Other objects will appear from time to time in the specification and claims.

My invention is illustrated more or less diagrammatically in the accompanying drawings, wherein:

Figure 1 is a longitudinal section with parts in elevation;

Figure 2 is a part section, part elevation along the lines 2-2 of Figure 1;

Figure 3 is a detail plan view of the parts shown in Figure 2;

Figure 4 is a section along the line 4-4 of Figure 1;

Figure 5 is a section along the line 5-5 of Figure 1;

Figure 6 is a section along the line 6-6 of Figure 1.

Like parts are indicated by like characters throughout.

A is a supporting bed plate. Projecting upwardly from the center thereof is a relatively thick perpendicular insulating plate A¹. This plate is centrally apertured for a flanged guide sleeve A² and there are arranged concentrically about this flanged guide sleeve A² a series of conductor tubes A³ A⁴ arranged in two concentric groups. In my preferred exemplification, the inner group of tubes are twenty-four in number and there is one for each hour of the day, the outer group having sixty in number, one for each minute in the hour, though the arrangement and number of these tubes might vary depending on the circumstances of their use. These conducting tubes or sockets extend clear through the insulating plate A¹ and are slightly flared as at A⁵ on the front side. At the back of the plate, these tubes or conductor sockets are provided with integral conductor fingers A⁶ A⁷. These fingers extend first outwardly from the

plate and then being bent inwardly toward the axis of the central sleeve A². These fingers are all out of contact with one another and the tubes or sockets themselves are insulated from one another by the plate A¹. Arranged concentric with the groups of contact fingers A⁶ A⁷ are two continuous conductor collars A⁸ A⁹, the maximum diameter of the collar A⁸ is preferably a little less than the diameter of the circle in which are located the ends of the fingers A⁶. The inward diameter of the collar A⁹ is preferably slightly greater than the diameter of the circle bounding the outer extremities of the fingers A⁷. The outer diameter of the collar A⁹ is preferably slightly less than the diameter of the circle bounding the inner ends of the fingers A⁷ and these two conductor rings mounted as they are on the insulating plate A¹ are insulated from each other and from all the conductor fingers or sockets. Conductors A¹⁰ A¹¹ lead from the collars A⁸ A⁹ to any suitable mechanism or indicator which is to be controlled by current operated by the switch.

The insulating plate A¹ is held in position on the base A by a flange B and by a cradle B¹, which cradle is bolted to a base as at B² and to the insulating plate A¹ at B³. B⁴ is a guide ring contained within the cradle B¹ mounted on the lower half of the front face of the plate A¹ concentric with the outer diameters of the sockets A³ in the outer group. Associated with the cradle B¹ is an end plate B⁵ closing the outer end of the cradle and projecting upwardly from the bed plate A. This end plate is slotted at B⁶, the slot terminating in a semi-cylindrical end concentric with the sleeve A². It is also bounded on its upper extremity by a horizontal bearing surface B⁷.

C is a program cylinder. It comprises spiders C¹ C¹ at either end joined by a holding bolt C². Clamped between these spiders are alternate insulating plates C³ and notched conductor plates C⁴. At each end are a plurality of heavier insulating plates C⁵ C⁶ of short diameter and there are spaced along the cylinder similar plates C⁶ which divide the notched conductor plates into four separate groups. These notched conductor plates and the insulated plates are perforated as indicated, there being in each plate as many perforations as there are conductor plates, insulating tubes C⁶ extend inwardly

through the line perforations and contain conductor rods C⁷, each rod being insulated from all the plates except one, the conductor rods and insulating tubes varying in length so that there is one rod and one tube terminating at each conductor plate, rods all projecting outwardly from the end of the program cylinder and being adapted each to penetrate one of the sockets A⁴, 10 as indicated. C⁸ C⁹ are rods carried in the insulator rings or plates C⁵, located about the outer periphery of the program cylinder just clearing the notched conductor discs. These rods project also beyond the end of 15 the program cylinder and are so spaced that one of them penetrates the sockets A³. The inner conductor rods in this case are twenty-four in number, there being one notched conductor plate for each hour of the day, the 20 outer rods are sixty in number, there being one for each minute of the hour just as in the case of the sockets above referred to. Each of the conductor plates are notched with sixty notches, one for each minute, one 25 for each conductor rod. C⁹ is a removable spring contact fork adapted to straddle one of the minute conductor rods, and penetrate its appropriate notch in one of the hour plates, there may be one or more of these 30 forks. They close when in place electric circuits between selected hour plates and minute wires and it is by adjusting these various spring fingers that a program may be set up on the program cylinder. The outer 35 end of the program cylinder is finished by a cap C¹⁰ which has a flange bent up around the two insulating plates C⁵ adjacent thereto. This flange may be marked to indicate minutes for ease in adjusting or setting up the 40 program, the hours being divided into groups of six by the insulating rings, are easily determined. Projecting outwardly from the end of the program cylinder are two pins C¹⁰. These pins are adapted to 45 engage the horizontal wall B⁷ on the end plate B⁵ to hold the program cylinder against rotation as it is being positioned. The tension screw C² extends beyond such pins and has threaded thereon a hand wheel 50 C¹¹ with a channelled hub C¹² adapted to penetrate the notch B⁶ and to be guided thereby. The flanges formed of the channel engage the sides of the end plate and hold the hand wheel against longitudinal movement meanwhile permitting its free rotation. 55

The program cylinder may be disassembled from the rest of the apparatus by rotating the hand wheel to draw the cylinder to the right, guided as it is by the pins C¹⁰. 60 The contact wires or rods will move out along the sockets until completely withdrawn, at which position the cylinder will still remain in place being held at one end by the pins C¹⁰ and screw C² and at the 65 other by the engagement of the outer con-

ductors C⁸ with the guide ring B⁴. In this position the program cylinder can be lifted out of its cradle and taken away. When changes or adjustments have been made the cylinder may be returned and held in its 70 cradle with the pins C¹⁰ and screw C² and hub C¹² engaging the end plate B⁵ and the outer conductors C⁸ engaging the guide ring B⁴. Then a rotation of the hand wheel will force the cylinder forwardly into position 75 seating all the conductor pins in the sockets.

The pressure on the hub C¹² will force the inner flange into a recess C¹³ on the inner wall of the end plate B⁵ so as to lock the outer end of the cylinder against displacement in a vertical direction as shown in the drawings and thus the cylinder will be locked in place at both ends.

The bed A is apertured at D. The inner end of the aperture is bounded by an upwardly turned perforate flange D¹; in opposition to this flange is a perforate flange D² projecting upwardly from a slide D³ on the bed plate. This slide D³ is slotted at D⁴ to engage a ring D⁵ on the bed plate and a lock screw D⁶ projecting upwardly from the bed plate and associated with a thumb nut D⁷ whereby the slide may be moved toward and from the flange D¹ and toward and from the insulating plate A¹. Projecting upwardly from the slide D³ is an insulating support D⁸ having a central guide sleeve D⁹, a plurality of conductor sockets D¹⁰ concentrically arranged therearound with inwardly extending contact fingers D¹¹ 100 and a continuous conductor ring D¹². D¹³ is a housing and D¹⁴ a conductor leading from a holding screw D¹⁵ associated with the conductor ring D¹².

E is a switch frame provided with pins E¹ E² to engage the flanges D¹ D² when the parts are assembled as shown. Projecting upwardly from this frame are supporting members E³ E⁴, ratchet dog supporting members E⁵ E⁶ and dogs E⁷ E⁸. The members E⁴ E⁵ carry an outer switch arbor E⁹ and inner switch shaft E¹⁰ associated with ratchets E¹¹, E¹² and E¹³ whereby the arbors E⁹ E¹⁰ may be rotated by an electro magnet E¹⁴ at varying rates of speed. The outer 115 arbor E⁹ carries a switch head E¹⁵, the inner arbor a head E¹⁶. In these heads are double switch arms E¹⁷ E¹⁸ E¹⁹ and E²⁰ in electric contact with one another but insulated from the arbors. Thus these pairs of switch arms 120 E¹⁷ E¹⁸ E¹⁹ E²⁰ serve as the switch arbors are rotated to close electric contacts between the rings A⁸ and fingers A⁶ in one pair and the rings A⁹ and fingers A⁷ in another pair.

Thus when these fingers reach the hour and minute combination selected by the positioning of the spring fork C⁹ a circuit is closed through the system between the two conductors A¹⁰ A¹¹. 125

The other end of the arbor switch assem-

bly carries a switch head F having insulated switch arms F¹ adapted to engage the fingers D¹¹ and the conductor D¹².

When it is desired to disassemble this part 5 of the structure, the thumb screw D⁷ is released, the slide D³ is drawn back, freeing the end of the shaft E¹⁰ from engagement with the sleeve D⁹ and the pin E² from engagement with the flange D². Then the 10 switch body can be moved slightly to the left freeing the pin E¹ from the flange D¹, and the end of the arbor E¹⁰ from the sleeve A². The switch fingers pass out freely owing to the concentricity and spacing of the 15 conductor rings and the switch may be removed for adjustment or correction.

It will be evident that while I have shown in my drawings an operative device, still many changes might be made in the size, 20 shape and disposition of parts without departing materially from the spirit of my invention and I wish therefore that my showing be taken as in a sense diagrammatic.

The recess C¹⁴ is provided on the outer 25 side of the end plate B⁵ to engage the hub C¹² when the hand wheel C⁴ is rotated to withdraw the member C. This prevents upward displacement of the member C until after the pins A⁵ are out of engagement with 30 the sockets A³ A⁴.

I claim:

1. In a switch assembly, a cradle, a fixed terminal plate and a removable circuit selecting cylinder adapted to lie within the 35 cradle in working relation to the terminal plate, the plate being located at one end of the cylinder.

2. In a switch assembly, a cradle, a fixed terminal plate and a removable circuit selecting cylinder adapted to lie within the 40 cradle in working relation to the terminal plate, means associated with each end of the cylinder for fixing it in proper working relation with respect to the terminal plate, the plate being located at one end of the 45 cylinder.

3. In a switch assembly, a cradle, a fixed terminal plate and a movable circuit selecting cylinder adapted to lie within the 50 cradle in working relation to the terminal plate, means associated with each end of the cylinder for fixing it in proper working relation with respect to the terminal plate, said means comprising in part, a guide 55 segment adjacent the terminal plate adapted to support the underside of the cylinder, the plate being located at one end of the cylinder.

4. In a switch assembly, a cradle, a fixed 60 terminal plate and a removable circuit selecting cylinder adapted to lie within the cradle in working relation to the terminal plate, means associated with each end of the cylinder for fixing it in proper working

relation with respect to the terminal plate, 65 said means comprising in part, a guide segment adjacent the terminal plate adapted to support the underside of the cylinder, the cylinder having a plurality of conductor pins projecting from the end thereof toward 70 the terminal plate, the plate having a plurality of conductor sockets adapted to receive said pins, the guide segment being adapted to support some of those pins and 75 guide them into the sockets.

5. In a switch assembly, a cradle, a fixed terminal plate and a removable circuit selecting cylinder adapted to lie within the cradle in working relation to the terminal plate, means associated with each end of 80 the cylinder for fixing it in proper working relation with respect to the terminal plate, said means comprising in part a slotted guide wall at the end of the cradle, a holding screw adapted to engage said slot, guide 85 pins adapted to engage said wall at points removed from the holding screw and a nut associated with the screw and the wall for longitudinally forcing the cylinder toward 90 the terminal plate.

6. In a switch assembly, a cradle, a fixed terminal plate and a removable circuit selecting cylinder adapted to lie within the cradle in working relation to the terminal plate, means associated with each end of 95 the cylinder for fixing it in proper working relation with respect to the terminal plate, said means comprising in part a slotted guide wall at the end of the cradle, a holding screw adapted to engage said slot, guide 100 pins adapted to engage said wall at points removed from the holding screw and a nut associated with the screw and the wall for longitudinally forcing the cylinder toward 105 the terminal plate, means interposed between the wall and nut for preventing lateral movement of the cylinder when the nut and screw is tightened to seat it in place in the cradle.

7. In a switch assembly, a cradle, a fixed 110 terminal plate and a removable circuit selecting cylinder adapted to lie within the cradle in working relation to the terminal plate, means associated with the cradle and cylinder for moving the cylinder therein 115 toward the terminal plate and locking it in place and means for holding the cylinder against rotation with respect to the cradle.

8. In a switch assembly, a cradle, a fixed 120 terminal plate and a removable circuit selecting cylinder adapted to lie within the cradle in working relation to the terminal plate, means associated with the cradle and cylinder for moving the cylinder therein toward the terminal plate and locking it in 125 place and means for holding the cylinder against rotation with respect to the cradle, said means being adapted to guarantee that

the cylinder can only be seated in the cradle in a single selected angular relation with respect to the terminal plate.

9. In a switch assembly, a fixed socketed terminal plate, a removable circuit selecting cylinder, contact pins projecting therefrom adapted to engage the sockets in the plates, means for supporting the cylinder, moving it longitudinally toward and into relation with respect to the plate and means adapted to guide the contact pins into engagement with the sockets.

10. In a switch assembly, a fixed socketed terminal plate, a removable circuit selecting cylinder, contact pins projecting therefrom adapted to engage the sockets in the plates, means for supporting the cylinder, moving it longitudinally toward and into relation with respect to the plate and means adapted to guide the contact pins into engagement with the sockets, said guide means comprising a guide segment associated with the plate adapted to support some of the contact pins as they commence their penetration of the sockets.

11. In a switch assembly, a fixed socketed terminal plate, a removable circuit selecting cylinder, contact pins projecting therefrom adapted to engage the sockets in the plates, means for supporting the cylinder, moving it longitudinally toward and into relation with respect to the plate and means adapted to guide the contact pins into engagement with the sockets, an abutment opposed to the plate, a hand wheel rotatable on the abutment and a screw projecting from the cylinder and in threaded engagement with the wheel whereby the rotation of the hand wheel forces the cylinder toward the plate.

12. In a switch assembly, a fixed socketed terminal plate, a removable circuit selecting cylinder, contact pins projecting therefrom adapted to engage the sockets in the plates, means for supporting the cylinder, moving it longitudinally toward and into relation with respect to the plate and means adapted to guide the contact pins into engagement with the sockets, said guide means comprising a guide segment associated with the plate adapted to support some of the contact pins as they commence their penetration of the sockets, an abutment opposed to the plate, a hand wheel rotatable on the abutment and a screw projecting from the cylinder and in threaded engagement with the wheel whereby the rotation of the hand wheel forces the cylinder toward the plate.

13. In a switch assembly, a fixed socketed terminal plate, a removable circuit selecting cylinder, contact pins projecting therefrom adapted to engage the sockets in the plates, means for supporting the cylinder, moving it longitudinally toward and into relation with respect to the plate and means adapted to guide the contact pins into engagement

with the sockets, an abutment opposed to the plate, a hand wheel rotatable on the abutment and a screw projecting from the cylinder and in threaded engagement with the wheel whereby the rotation of the hand wheel forces the cylinder toward the plate, the hand wheel being removable from the abutment as a unit after the cylinder has been fully retracted from the terminal plate.

14. In a switch assembly, a fixed socketed terminal plate, a removable circuit selecting cylinder, contact pins projecting therefrom adapted to engage the sockets in the plates, means for supporting the cylinder, moving it longitudinally toward and into relation with respect to the plate and means adapted to guide the contact pins into engagement with the sockets, said guide means comprising a guide segment associated with the plate adapted to support some of the contact pins as they commence their penetration of the sockets, an abutment opposed to the plate, a hand wheel rotatable on the abutment and a screw projecting from the cylinder and in threaded engagement with the wheel whereby the rotation of the hand wheel forces the cylinder toward the plate, the hand wheel being removable from the abutment as a unit after the cylinder has been fully retracted from the terminal plate.

15. In a switch assembly, a main frame, an insulated terminal plate fixed thereon, a plurality of contact fingers arranged in concentric groups on the plate, a plurality of conductor rings arranged one inside each group of fingers, a switch operating assembly mounted on and removable from the main frame as a unit, pairs of associated switch arms carried thereby, one arm of each pair engages a group of fingers, the other an adjacent ring, the mounting of the switch operating assembly being such that when it is removed from the main frame, the switch arms are automatically disengaged from the fingers and rings.

16. In a switch assembly, a main frame, an insulated terminal plate fixed thereon, a plurality of contact fingers arranged in concentric groups on the plate, a plurality of conductor rings arranged one inside each group of fingers, a switch operating assembly mounted on and removable from the main frame as a unit, pairs of associated switch arms carried thereby, one arm of each pair engages a group of fingers, the other an adjacent ring, the mounting of the switch operating assembly being such that when it is removed from the main frame, the switch arms are automatically disengaged from the fingers and rings, the switch operating assembly including a working shaft, the terminal plate being apertured concentric with the groups of contact fingers to removably engage and center the shaft.

17. In a switch assembly, a main frame,

an insulated terminal plate fixed thereon, a plurality of contact fingers arranged in concentric groups on the plate, a plurality of conductor rings arranged one inside each group of fingers, a switch operating assembly mounted on and removable from the main frame as a unit, pairs of associated switch arms carried thereby, one arm of each pair engages a group of fingers, the other an adjacent ring, the mounting of the switch operating assembly being such that when it is removed from the main frame, the switch arms are automatically disengaged from the fingers and rings, the switch operating assembly including a working shaft, the terminal plate being apertured concentric with the groups of contact fingers to removably engage and center the shaft, the distance of the working surface of conductor rings and contact fingers from the face of the terminal plate increasing progressively from the center outwardly.

Signed at Chicago county of Cook and State of Illinois, this 22 day of December, 1924.

HULBERT SANNER.
